DESIGN FOR DISPLAY CARD

William C. McKenna, Baltimore, Md., assignor to
The Emerson Drug Company of Baltimore City,
Baltimore, Md., a corporation of Maryland

Application November 10, 1939, Serial No. 88,199

Term of patent 14 years

To all whom it may concern:

Be it known that I, William C. McKenna, a citizen of the United States, residing at Baltimore City, State of Maryland, have invented a new, original, and ornamental Design for a Display Card, of which the following is a specification, reference being had to the accompanying drawing, forming part thereof.

The dominant features of my design reside in the portions shown in full lines.

I claim:

The ornamental design for display card, substantially as shown and described.

WILLIAM C. MCKENNA.
